UNITED STATES PATENT OFFICE.

WILLIAM CONRAD NEIN, OF NEW YORK, N. Y., ASSIGNOR OF ONE-THIRD TO MAY A. HOLDEN, ADMINISTRATRIX OF GEORGE A. HOLDEN, DECEASED, AND ONE-THIRD TO THOMAS W. VARLEY, OF NEW YORK, N. Y.

TRAIN STOP AND SIGNALING DEVICE.

1,269,567.

Specification of Letters Patent. Patented June 11, 1918.

Application filed July 28, 1914. Serial No. 853,572.

To all whom it may concern:

Be it known that I, WILLIAM CONRAD NEIN, citizen of the United States, and resident of borough of Manhattan, in the county 5 of New York and State of New York, have invented certain new and useful Improvements in Train Stop and Signaling Devices, of which the following is a specification.

This invention relates to means for automatically stopping or slowing down railway vehicles in case of danger and for giving warning by signals.

The main object of the invention is to provide improved apparatus whereby the 15 above results may be certainly and safely accomplished.

Another object of the invention is to provide apparatus whereby proper operation will be secured regardless of the relative 20 position of the vehicle upon the rails.

Another object of the invention is to provide apparatus of the character described whereby permanent magnets are employed as track magnets in an improved way.

25 Other and ancillary objects of the invention will appear hereinafter.

In the accompanying drawings, which illustrate the invention,

Figure 1 is a diagrammatic side elevation 30 of a vehicle and track illustrating the invention.

Fig. 2 is a diagrammatic end elevation of the apparatus of Fig. 1.

Figs. 3 and 4 are enlarged views of side 35 and end elevations respectively, of a pair of vehicle wheels on one side and a coöperating track magnet, showing details of the track magnet.

Fig. 5 is a diagram showing the electrical 40 connections of a signal and stop system illustrating the invention.

Fig. 6 is a sectional view of an air control valve.

Fig. 7 is a diagrammatic side elevation of 45 apparatus showing a modification.

Figs. 8 and 9 are respectively side and end elevations of an air controlling device employed in Fig. 7.

Figs. 10 and 11 are respectively diagrammatic views in side elevation and plan of a further modification,

Figs. 12 and 13 are respectively diagrammatic views in plan and end elevation of a further modification.

Figs. 14 and 15 are respectively diagrammatic views in plan and side elevation of a further modification, and

Figs. 16 and 17 are respectively side and end elevations of a rail section having high reluctance.

Referring to the drawings, and first to Figs. 1 and 2, which show in diagram an arrangement of car and magnetic circuits, 1 and 2, are the rails upon which run the vehicle wheels. The wheels are, as usual, in

5 pairs, the wheels 3 and 4 running upon the same rail, one ahead of the other. These wheels are connected by axles 5 and 6 respectively with corresponding wheels upon the other rail. Thus the wheel 3 is connected with the wheel 7 by the axle 5. The wheels and axles may be constructed of the usual iron, which as is well known, is of good magnetic conductivity. Connected between two

60 pairs of the same rail is a magnet yoke having as good magnetic connection as possible with the wheels 3 and 4 at its ends 8 and 9. A tongue 10 pivoted at 11 is normally held by a spring 12 to close a circuit including the variable resistance 13, electromagnet 14 and battery 15.

A piece of insulation 16 may be inserted in the yoke to prevent wandering of the electric current from the circuit of the battery 15. When

65 magnetism of the sufficient amount passes through the magnetic yoke between the wheels, the tongue 10 may be attracted, overcoming the spring 12 when the circuit of the magnet 15 will be opened at the contact 17. Along the track way under each rail is a magnet having the longitudinal portion 18 a permanent magnet, while the legs 19 and 20 at right angles to the end thereto form cores for the coils 21 and 22. The ends of the cores are presented to the rails in

70 such manner as to make as good magnetic connection as possible. In some cases, however, where the motive power is electricity, it may be desirable to insulate the limbs 19

75 and 20 by inserting insulation as 23 and 24 between the limbs and the rails. It is desired that magnetism emanating from the

limbs 19 and 20 shall pass through the wheels and the yoke between them when the wheels are in proper relation to the track magnet and to this end the rail section 25 is inserted in the track rail, this section being of high magnetic reluctance, such as manganese steel. The coils 21 and 22 may be energized from a suitable source, as a battery 26. It is also desirable to provide an adjusting resistance 27. The circuit may be controlled in a manner as will appear hereinafter, or in other suitable ways to produce the desired result. It may be stated that in the embodiment shown, the coils 19 and 20 are wound in such directions as to oppose the magnetism which the permanent magnet 18 tends to set up and normally the magnetism passing through the wheels on the rail and the yoke between them will not be sufficient to pull down the tongue 10 as the wheels pass the track magnet structure. At such times as it is desired to give a signal, however, the circuit of the coils 21 and 22 will be broken, so that the permanent magnet will exert its full strength. The magnetism then sent through the yoke between the wheels on the rail will pull down the tongue 10 and deenergize the electromagnet 14 whereby signaling devices are set in operation.

From an examination of Fig. 2 it will be seen that a magnet structure like that shown in Fig. 1 is placed beneath each rail, the two being opposite each other. Only one yoke between the pair of wheels on one side is shown and it is apparent that this will become subject to the magnetism of the track magnet on one side or the other, according to the relation of the vehicle or train to the track. A pair of wheels with the magnetic yoke as described being above one rail they will be above the other rail if the train or vehicle is turned end for end.

Details of a track magnet structure which may be advantageously employed are shown in Figs. 3 and 4. The permanent magnet 18 is preferably formed of a plurality of bars, plates or laminæ 28 clamped together by means of clamps 29 and 30. Clamped to the foot of the rail are the members 31 and 32 making intimate magnetic contact therewith. Between the clamps 31 and 32 and the clamps 29 and 30 is inserted a bobbin comprising the winding 19 about the core 20 and the whole is clamped together by bolts 33. Each end of the track magnet structure is secured to the rail in the same way and the manganese section 25 already referred to prevents short circuiting of the magnetism from the wheels.

The insulation of the track magnet structure from the track as indicated at 23 and 24 in Fig. 1 may be included between the clamps 31 and 32 and the limb 20 in Fig. 4 and of course in order to have good insula-

tion at this point it will be necessary to insulate the bolts 33 by bushings or otherwise, so that they will not establish electrical connection between the clamps 31 and 32 and the limb 20.

Referring now to Fig. 5 there is therein shown in diagram three blocks, the track rails 1 and 2 being divided into the blocks by insulated sections 35, 36, 37 and 38, there being shown small fractions of a block at each end. Each of the blocks comprises the same apparatus and therefore a reference to the left-hand block will be sufficient to illustrate the structure in each of them. It will be seen that the block comprises track magnets 39, 40 and 41 each having its horizontal part, that is, in this case the permanent magnet, extending longitudinally of the rail. Directly opposite each of the track magnets 39, 40, 41 and beneath the rail 2 are track magnets 42, 43 and 44 of the same character in all respects but with this difference, that the polarities of the permanent magnets 42, 43 and 44 are reversed in position with relation to the permanent magnets of the structures 39, 40 and 41, so that when a train moves along the track it will encounter a north pole on one side when it encounters a south pole on the other side. The coils upon the limbs of track magnets which are opposite each other are connected in series and in circuit with a battery 45, a variable resistance 46 and the relay contacts 47. As before noted, the coils of the track magnet structures are wound and arranged to oppose the magnetism which tends to be set up by the permanent magnets. The magnets 40 and 43 are similarly arranged, having their coils in circuit with the battery 48, the adjustable resistance 49 and the relay contacts 50. Similarly, the coils of the magnets 41 and 44 are connected in series with the battery 51, the relay contacts 52 and the variable resistance 53.

The relay magnets 54, 55 and 56 which respectively control the contacts 47, 50 and 52 are connected in series with each other through the back contact 57 of the track relay 58 in their own block, the variable resistance 59, the battery 60 and the forward contacts 61 of the track relay 62 of the block ahead. A vehicle 63 is shown in the block and is supposed to be moving in the direction as indicated by the arrow. Connected between the track rails is a battery 64. Between the poles of the track magnets rail sections 65 to 70 inclusive material of high magnetic reluctance, such as manganese steel, are inserted as before referred to. It will also be noted that there is a vehicle 71 in the right-hand block.

Referring now to the left-hand block, it will be seen that when the vehicle is in the block, the battery 64 will be short-circuited, and the track relay 58 deenergized. At all

other times the track relay is energized and holds its forward contacts closed.

The block ahead of the one containing the vehicle 63 being clear, when a pair of the 5 wheels upon the same rail are presented to the poles of a track magnet, and magnetic and electrical circuits are arranged as shown in Fig. 1, the magnetism would tend to be set up through the magnetic circuit on the 10 vehicle through the wheels by the permanent magnet. The block ahead being clear, however, the circuit of the magnets 54, 55 and 56 will be closed, and the relay contacts 47, 50 and 52 will be closed. The magnet 15 coils on the track magnets will therefore be energized, and, as they oppose the magnetisms of the permanent magnets, no operative magnetism will pass to the vehicle, and the progress of the vehicle will not be 20 interfered with.

If now we consider that a vehicle is in the middle block, a condition of danger will exist for it by reason of the existence of the vehicle 63 in the block ahead of it. The 25 track relay 58 will therefore have its contacts open, and the circuit of the local relays will be broken. This deenergizes the coils of the track magnets which permits the permanent magnet of the track magnet to 30 force an operative amount of magnetism through the wheels and yoke between them. When the wheels of the vehicle are presented to the magnet poles, for instance, as shown in Fig. 1, an operative amount of 35 magnetism being sent through the wheels and the yoke between them, the tongue 10 will be attracted, opening the contacts 17 and deenergizing the electromagnet 14. The deenergizing of this normally energized 40 magnet may set in operation various audible, visible or other signal devices and may also operate to automatically operate the air brakes.

In Fig. 6 is shown a device for controlling 45 the air brake system. This device comprises a casing 75 in which is a slide valve 76 controlling connections 77 with the train line, 78 with the atmosphere and 79 through which air from the main reservoir is supplied to the train. The passage 80 leads to the main reservoir. The slide 76 is operated by means of a rod 81 to which are secured the pistons 82 and 83, the latter being larger than the former as shown. A passage 50 84 connects the main reservoir with a chamber in which moves the piston 83, this connection being governed by means of a valve 85. Exhaust from the chamber of the piston 83 may take place through the port 86 55 controlled by a valve 87, communication with the atmosphere being made through a passage 88. The valves 85 and 86 are mounted upon the same stem and connected with the plunger 89 of a magnet having two 60 windings 90 and 91. The valve 85 is seated

when the plunger is lowered, while this valve is opened and the valve 86 seated when the plunger is lifted. The windings and plunger are so constructed and arranged that the magnetomotive force of the winding 90 is sufficient to maintain the plunger raised after it has been raised, but is not sufficient to lift the plunger after it has dropped. The winding 91, however, is so constructed and connected as to act in conjunction with the winding 90 and supply the additional magnetomotive force necessary to lift the plunger after it has dropped; the winding 91 can then be deenergized, the winding 90 being sufficient to hold the plunger after it has been lifted as above noted. The winding 91 may be energized from the battery 92 in a circuit which includes the hand switch 93, the adjustable resistance 94 and the normally open contacts 95 which are 75 pushed together by the projection 96 upon the piston rod 81 when the pistons have moved to their left hand position. The electromagnet shown in Fig. 6 corresponds to the electromagnet 14 shown in Figs. 1 and 2, and the manner of energizing the winding 90 is shown in those figures.

From the foregoing it will be seen that, the plunger 89 having been lifted, the normally closed circuit including the battery 95 15 of Fig. 1 will keep the plunger lifted. The valves will occupy the positions as shown when pressure from the main reservoir is admitted to the faces of both of the pistons. The piston 83 being larger, the 100 slide valve is pushed to the right as shown when the main reservoir is connected with the channel 79 and the train line is cut off from the atmosphere. In this condition the 105 brakes are off. If now a vehicle arranged as shown in Fig. 1 should have its wheels on one rail presented to the poles of a track magnet in the right hand block, nothing would take place as the coils on this magnet would be energized and neutralize the 110 permanent magnet. If, however, the vehicle should enter the middle block, when the 115 wheels on the rail were presented to the poles of a track magnet, the magnetism therefrom would traverse the yoke between the wheels (the magnetism of the permanent magnet being unopposed because of the presence of a vehicle in the next block ahead), the winding 90 would be deenergized and the plunger 120 would drop. This would close the valve 85 and open the valve 87. The air pressure 125 would thus be shut off from the piston chamber 83 and it would be connected with the atmosphere. The main reservoir pressure on the small piston 82 would predominate and the slide valve moved toward the left. The main reservoir would thus be shut off, the 130 train line connected with atmosphere and brakes applied. This would occur upon the passage of the first pair of magnets at the

right hand of the middle block and the engineer would be obliged to stop until such time as he could close the switch 93, when the pull of the winding 91 would be added to that of the winding 90 (after the wheels had moved out of the influence of the track magnet). The plunger would be then lifted and the slide valve moved to the right, whereupon the brakes would be removed.

10 In order to prevent ill-considered or hasty operation in taking off the brakes, the switch 93 would preferably be located at some point where it would be necessary for the engineer to get out of his cab or take some other well-considered action before effecting its operation. The brakes having been removed, the train may proceed until the track magnets at the middle of the block have been encountered when the brakes may again be applied.

15 and the engineer may remove them and pass on as before. This is also true of the track magnets at the left hand end of the block. It will thus be seen that the engineer will be given warning three times, beginning at

20 the entrance of the block, that the block ahead is occupied and a condition of danger exists and will have plenty of opportunity to take suitable action. On the other hand, he is not stalled; he may remove the obstruction to his progress, and proceed as may seem advisable.

Referring to the modified form of apparatus shown in Figs. 7, 8 and 9, the track magnet comprises a permanent magnet 18', the windings 21' and 22', the limbs 19' and 20' with insulating sections 23' and 24' from the track rail 2' in which is inserted the manganese section 25' and on which rest the wheels 3' and 4', between which extends the

25 yoke having the ends 3' and 9' presented to the wheels, the coils 21' and 22' being placed in circuit with a battery 26' and a variable resistance 27'. All of this structure is the same as that of Figs. 1 and 2 except that instead of having a magnetic tongue as 10 actuated to affect an electric circuit, this magnetism acts upon an air valve. In the yoke between the wheels is a gap 100 across which extend magnetic

30 controlling devices for the air brakes. These magnetic devices can be best explained in connection with Figs. 8 and 9 to which reference is now made. Secured to each of the yoke members are three springs 101, 102 and 103 at different distances from the magnetic yoke. Each of the springs carries a block of iron 104, 105 and 106, formed at their tops with points 107, 108 and 109 adapted to act as pin valves in holes in the

35 receptacle 110. The hole corresponding to the block 106 which is nearest to the magnetic yoke is the smallest, that corresponding to the block 105 is smaller while that corresponding to block 104 which is farthest away from the magnetic yoke is the largest.

These holes are normally held closed by the springs 101 to 103. The receptacle 110 may be in communication with the train line so that escape of air bled from this receptacle by the lowering of one or more of the blocks 104 to 106 will apply the brakes, or the receptacle 110 might be a tank under pressure, from which air bled by the lowering of the blocks 104 to 106 is led into an air valve, which will open the train line and close the main reservoir of the air brake system.

The blocks 104, 105 and 106 being mounted directly over the gap 100 in the magnetic yoke, any magnetism passing through this yoke will tend to pull the blocks downwardly. The block 106 being nearest to the gap will be acted upon most strongly by a given magnetization, the block 105 will be pulled down by the somewhat stronger magnetization than is required to pull down the block 106, while the block 104 will require a still stronger magnetization to depress it. When depressed, a block and spring will occupy a position as shown in dotted lines in Fig. 8. When, therefore, a vehicle, equipped as just described, passes over a track magnet, if there is sufficient magnetization sent through the wheels and yoke by the magnet, one or more of the pin valves 107 to 109 will be opened.

With the arrangement of a vehicle as just described, when a vehicle is in the right hand block of the apparatus as indicated in Fig. 5 it will be noted that there is no vehicle in the middle block so that the vehicle may pass through the right hand block without any effect upon its apparatus, the magnetism of the permanent magnets being neutralized by the windings of the track magnets. When the vehicle enters the middle block, there being a vehicle in the next block ahead, the neutralizing electromagnetic part of the track magnets will be de-energized so that the permanent magnets will force their magnetism through the magnetic circuits through the wheels as the track magnets are passed. The first track magnet to be encountered upon entering the middle block is made of such strength that the block 106 will be depressed, but is not sufficient to cause depression of either of the blocks 104 or 105. The permanent magnet of the middle track magnets of the block are of such strength, that block 105, but not 104, will be pulled down, while the strength of the permanent magnets at the left hand end of the block will pull down the block 104. The result is that upon encountering the first track magnet the receptacle 110 will be bled, but at a slow rate so that it will require considerable time to bleed the train sufficiently to apply the brakes or to obtain sufficient air through the opening to actuate a valve, where such a means of applying the brakes is used. If the train proceeds,

when it encounters the next track magnet the pin valve corresponding to the block 105 will be opened, allowing greater rapidity of bleeding so that the brakes will be quickly set. If the train proceeds until it encounters the next and last track magnet in the block, the pin valve corresponding to the block 104 will be opened and, the position then being close to the danger signal, a sufficient vent will be given to the receptacle 110 to quickly set the brakes.

As the vehicles pass over the magnets it will be apparent that the pull of the magnetism upon the blocks 104 to 106 will be quite brief. It is desired, however, that while they should be normally closed and should return to closed position after having been opened, this return movement should be retarded so as to give effect to the brake operation as described. To this end a retarding means for preventing the quick return of the blocks 104 to 106 is provided. There is a dash-pot 111 corresponding to each of the springs 101 to 103. Supported by an up-right spring 112 fixed to the dash-pot piston 113 is a latch 114 which engages the end of the spring when it is depressed. The returning force of the spring causes it to rise but slowly on account of the slow movement of the dash-pot piston. When the spring has nearly or quite reached its uppermost position, the latch is engaged by a stationary deflector 115 which forces the latch out of engagement with the spring. The latch with the piston then returns to its lowest position in readiness for a repetition of the operation.

It thus appears that on account of the different strengths of the permanent magnets along the track in the block, the engineer is signaled and the brakes gradually brought into operation, so that the engine-driver has ample warning of the stop required by danger in the next block, the train is slowed down so that the stop can be safely made even if the engineer takes no action, and finally the stop is automatically made.

Referring to the modification as shown in Figs. 10 and 11, there are the track rails 116 and 117 with manganese sections 118 in each and with a track magnet bridging each of the manganese sections. Each of the said track magnets comprises the permanent magnet 119 extending along the rail and the windings 120 and 121 upon the iron limbs 122 and 123, these limbs being insulated if occasion requires (but otherwise making close contact with the rails) by insulating pieces 124. The magnetic windings which oppose the magnetomotive force of the permanent magnet are connected in circuit with a battery 125 and an adjustable resistance 126. Between two wheels 127 and 128 on each rail extend the magnetic yokes 129 and 130 respectively. Around

these yokes are wound coils 131 and 132. These coils are wound in opposite directions, so that they act in conjunction, the track magnets on opposite sides of the track being turned end for end, that is to say, a car approaching a pair of track magnets will encounter a north pole on one side of the track and a south pole on the other. The two windings 131 and 132 are connected in series in a closed circuit with the battery 133, the electromagnet 134 and the variable resistance 135. It is apparent that normally the circuit through the electromagnet 134 will be completed and that that magnet will be energized. This magnet may be that which controls an apparatus as shown in Fig. 6, as has been already described.

If now a vehicle is traveling in a block against which no danger is set, as for instance, in the right hand block of Fig. 5, there will be no effect upon the magnetic circuit on the vehicle by the track magnets as they are neutralized by the electromagnetic windings as before explained. When the vehicle travels into the next block, however, (the middle block of Fig. 5) the magnetism in the first pair of track magnets will not be neutralized. As the pairs of wheels between which the yokes extend come into the influence of the track magnets, magnetism will be built up in the yokes between the wheels, which will induce an electromotive force in the coils 131 and 132. As the wheels recede from the influence of the track magnets, the magnetism will decrease and electromotive force will be generated in these coils, but in the opposite direction, so that there will be a complete cycle of electromotive force generated in the coils as the wheels pass a pair of track magnets, this cycle consisting of two alternations as is well known. One of these alternations will be opposed to the electromotive force of the battery 133. When this occurs, it is apparent that the coil 134 will be de-energized. The three pairs of track magnets in a block are so proportioned as to strength that the electromotive force induced in the coils upon passing them will be equal and opposite (and therefore neutralizing that of the battery 133) at different speeds of the vehicle.

It is well known that the electromotive force induced in a conductor is equal to the product of the strength of the magnetic field and the speed of cutting of the lines of force. The permanent magnet of each of the track magnets of a pair which is first encountered when a block is entered against which a danger signal is set is made of such strength that the vehicle must be making a certain speed, say sixty miles an hour, in order to generate electromotive force in the coils 131 and 132 to neutralize that of the battery 133. The second track magnets encountered have

their permanent magnets of such a strength that the neutralization is effected at a certain speed, say thirty miles an hour, this of course requiring that the second pair of magnets should be stronger than the first. The third pair of track magnets are made still stronger, so that neutralization of the battery is effected at a still slower speed, say fifteen miles an hour. It thus appears that in passing through the block against which there is no danger signal set, the electromagnet 184 will continue to be energized. When a vehicle enters a block against which a danger signal is set, however, the magnet 184 will not be affected by the first pair of magnets, unless the train is running at a high rate of speed. If so, it will be checked. The next pair of magnets will require the engineer to run at a still lower rate of speed if he is not to be checked, while the third pair of magnets in the block requires a very low rate of speed. In fact, this third pair of magnets may be made so strong that in case of a home or interlocking signal, the brakes will be applied with scarcely any movement of the train at all, that is, it will be compelled to come to a stop.

Referring now to Figs. 12 and 13 the apparatus operates in a similar manner to that of Figs. 10 and 11 but differs therefrom in that the magnetic circuit on the vehicle is made from wheel to wheel through the car axles and through the track magnets in series so that one pair of wheels and the track magnet on one side form a yoke for the other pair of wheels and track magnet upon the other side. The track magnets bear the same relation to the rails and are of reversed polarity on opposite sides as before and the rails have the manganese steel sections inserted in them. Electromagnet 149, controlling apparatus as shown in Fig. 6 as before described, is connected in series in a closed circuit with a battery 141, a variable resistance 142 and coils 143, 144, 145 and 146 which encircle the wheels below their axles. In these drawings, Figs. 12 and 13, the track magnets are indicated at 147 and 148, while the coils opposing the magnetomotive force of the permanent magnets and controlled by the track relays, as described, are indicated at 149 and 150, these coils being connected in series with a battery 151 and a variable resistance 152. When wheels arranged as described approach a track magnet which is not neutralized the building up and collapsing of the magnetic field which will be set up through the circuit formed by the magnets on opposite sides of the track, the wheels and axles, will induce electromotive force in the circuit of the coil 140 which may operate to neutralize it under various conditions as before described.

Referring to Figs. 14 and 15, the device differs from that shown in Figs. 12 and 13 in

that, instead of having the inductive coils for neutralizing the battery about the wheels, they are placed about the axles. Thus in the apparatus of Figs. 14 and 15, the signal or brake operating magnet 161 is connected in series with the coils 162 and 163 wound about the axles 164 and 165, it being understood that in both this and in that of Figs. 12 and 13, the coils are wound to avoid neutralizing each other. Also, in the circuit of the magnet 161 is the battery 166, which normally energizes it, and also the variable resistance 167. This device obviously will operate in a similar way to that described in connection with Figs. 12 and 13.

While the inclusion of manganese steel sections in the rails has been referred to and in many cases will be desirable, it may be that the usual track rails, owing to proportions or material, will not shunt sufficient magnetism from the magnetic circuit on the vehicle to interfere with its operation. In such case it will be unnecessary to insert a section of rail of different quality or proportion, but the same track rail can be used throughout.

Where it is necessary to prevent shunting of the magnetism from the vehicle magnetic circuit it may be desirable instead of inserting a high reluctance section to place a coil between the poles of the track magnet, which coil will encircle the base of the rail, passing through a hole in the web. A structure of this character is shown in Figs. 16 and 17, wherein 170 represents the tread of the rail, 171 the base, 172 the web, and 173 the coil as just referred to. This coil may be energized from any suitable source. It is apparent that the magnetism will flow in opposite directions in the head and base of the rail respectively. The magnetomotive force of the coil should therefore be made strong enough to saturate the magnetic circuit in the rail. When this is done, the section of the rail so saturated will interpose substantially the resistance of an air gap to the passage of magnetism. If the rail were not saturated as described, the application of the coil might aid the shunting of magnetism from the vehicle instead of preventing it.

The track relays as 58, 62, etc., may operate semaphores as 174, 175, 176 in a well known manner to cause the semaphores to indicate "clear," "danger" or "caution." Apparatus whereby a track relay may so operate the semaphores is well known in the art and is not therefore shown. In Fig. 5, the semaphore 174 is at vertical showing "clear," there being assumed to be no vehicle in that block, a portion of which is shown at the extreme right. The semaphore at 175 is at horizontal showing "danger," there being a vehicle in the left hand block. There being no vehicle in the

middle block, the semaphore 176 is shown at an angle of 45° indicating "caution," while the semaphore 174 is at "danger," there being a vehicle in the right hand block.

While the invention has been illustrated in what is considered its best applications, it may have other embodiments without departing from its spirit, and is not, therefore, limited to the structures shown in the drawings.

I claim and desire to obtain by Letters Patent the following:

1. The combination with a wheeled vehicle traveling along a fixed line of way, of track rails, track magnets, adapted to have their magnetic circuits completed through wheels succeeding each other on the same rail, the poles of said track magnets being presented to wheels upon one side of said track, and means controlled by the magnetism in said circuits for slowing the vehicle.

2. The combination with a wheeled vehicle traveling along a fixed line of way, of track rails, track magnets, adapted to have their magnetic circuits completed through wheels succeeding each other on the same rail, the poles of said track magnets being presented to wheels upon one side of said track, and means controlled by the magnetism in said circuits for stopping the vehicle.

3. The combination with a wheeled vehicle traveling along a fixed line of way, of track rails, track magnets, adapted to have their magnetic circuits completed through wheels succeeding each other on the same rail, the poles of said track magnets being presented to wheels upon one side of said track, and means controlled by the magnetism in said circuits for affecting the brakes of said vehicle.

4. The combination with a wheeled vehicle traveling along a fixed line of way, of track rails, track magnets comprising permanent magnets, adapted to have their magnetic circuits completed through wheels succeeding each other on the same rail, the poles of said track magnets being presented to wheels upon one side of said track, and means controlled by the magnetism in said circuits for slowing the vehicle.

5. The combination with a wheeled vehicle traveling along a fixed line of way, of track rails, track magnets comprising permanent magnets, adapted to have their magnetic circuits completed through wheels succeeding each other on the same rail, the poles of said track magnets being presented to wheels upon one side of said track, and means controlled by the magnetism in said circuits for stopping the vehicle.

6. The combination with a wheeled vehicle traveling along a fixed line of way, of

track rails, track magnets comprising permanent magnets, adapted to have their magnetic circuits completed through wheels succeeding each other on the same rail, the poles of said track magnets being presented to wheels upon one side of said track, and means controlled by the magnetism in said circuits for affecting the brakes of said vehicle.

7. The combination with a wheeled vehicle traveling along a fixed line of way, of track rails, track magnets controlled by conditions in the block ahead, adapted to have their magnetic circuits completed through wheels succeeding each other on the same rail, the poles of said track magnets being presented to wheels upon one side of said track, and means controlled by the magnetism in said circuits for slowing the vehicle.

8. The combination with a wheeled vehicle traveling along a fixed line of way, of track rails, track magnets controlled by conditions in the block ahead, adapted to have their magnetic circuits completed through wheels succeeding each other on the same rail, the poles of said track magnets being presented to wheels upon one side of said track, and means controlled by the magnetism in said circuits for stopping the vehicle.

9. The combination with a wheeled vehicle traveling along a fixed line of way, of track rails, track magnets controlled by conditions in the block ahead, adapted to have their magnetic circuits completed through wheels succeeding each other on the same rail, the poles of said track magnets being presented to wheels upon one side of said track, and means controlled by the magnetism in said circuits for affecting the brakes of said vehicle.

10. The combination with a wheeled vehicle traveling along a fixed line of way, of track rails, track magnets comprising permanent magnets, adapted to have their magnetic circuits completed through wheels succeeding each other on the same rail, the poles of said track magnets being presented to wheels upon the same side of the track, a coil about the magnetic circuit on the vehicle through which the magnetic circuits of the track magnets are adapted to be completed, a closed circuit for said coil, a source of electromotive force and a translating device also included in said circuit.

11. The combination with a wheeled vehicle traveling along a fixed line of way, of track rails, track magnets comprising permanent magnets, adapted to have their magnetic circuits completed through wheels succeeding each other on the same rail, the poles of said track magnets being presented to wheels upon the same side of the track, a coil about the magnetic circuit on the vehicle through which the magnetic circuits of

the track magnets are adapted to be completed, a closed circuit for said coil, a source of electromotive force and a translating device also included in said circuit and means for controlling the flow of magnetism from the permanent magnet in the magnetic circuit.

12. The combination with a wheeled vehicle traveling along a fixed line of way, of track rails, track magnets comprising permanent magnets, adapted to have their magnetic circuits completed through wheels succeeding each other on the same rail, the poles of said track magnets being presented to wheels upon the same side of the track, a coil about the magnetic circuit on the vehicle through which the magnetic circuits of the track magnets are adapted to be completed, a closed circuit for said coil, a source of electromotive force and a translating device also included in said circuit and electromagnetic means for controlling the flow of magnetism from the permanent magnet in the magnetic circuit.

13. The combination with a wheeled vehicle traveling along a fixed line of way, of track rails, track magnets comprising permanent magnets, adapted to have their magnetic circuits completed through wheels succeeding each other on the same rail, the poles of said track magnets being presented to wheels upon the same side of the track, a coil about the magnetic circuit on the vehicle through which the magnetic circuits of the track magnets are adapted to be completed, a closed circuit for said coil, a source of electromotive force and a translating device also included in said circuit, and adapted to be operated by the electromotive force induced in it by the magnetic flux from said permanent magnet.

14. The combination with a wheeled vehicle traveling along a fixed line of way, of track rails, track magnets comprising permanent magnets, adapted to have their magnetic circuits completed through wheels succeeding each other on the same rail, the poles of said track magnets being presented to wheels upon the same side of the track, a coil about the magnetic circuit on the vehicle through which the magnetic circuits of the track magnets are adapted to be completed, a closed circuit for said coil, a source of electromotive force and a translating device also included in said circuit, and adapted to be operated by the electromotive force induced in it by the magnetic flux from said permanent magnet, and means for controlling the flow of magnetic flux from said permanent magnet.

15. The combination with a wheeled vehicle traveling along a fixed line of way, of track rails, track magnets comprising permanent magnets, adapted to have their magnetic circuits completed through wheels suc-

ceeding each other on the same rail, the poles of said track magnets being presented to wheels upon the same side of the track, a coil about the magnetic circuit on the vehicle through which the magnetic circuits of the track magnets are adapted to be completed, a closed circuit for said coil, a source of electromotive force and a translating device also included in said circuit, and adapted to be operated by the electromotive force induced in it by the magnetic flux from said permanent magnet, and means comprising a coil and a source of current for controlling the flow of magnetic flux from said permanent magnet.

16. The combination with a permanent magnet located in a trackway and connected with the rail on one side of the track so as to have its poles presented to longitudinally separated portions of the rail included in the magnetic circuit of the permanent magnet, a coil on said permanent magnet for diverting or choking the flow of flux from the permanent magnet from the track rail, when it is energized, a circuit and source of current including said coil, means for controlling said circuit whereby the coil may be energized or deenergized, wheels having traveling contact with said trackway and through which the magnetic circuit of said magnet is adapted to be closed, a coil about said magnetic circuit and a closed circuit including the last mentioned coil.

17. The combination with a permanent magnet located in a trackway and connected with the rail on one side of the track so as to have its poles presented to longitudinally separated portions of the rail included in the magnetic circuit of the permanent magnet, a coil on said permanent magnet for diverting or choking the flow of flux from the permanent magnet from the track rail, means for controlling said circuit whereby the coil may be energized or deenergized, wheels having traveling contact with said trackway and through which the magnetic circuit of said magnet is adapted to be closed, a coil about said magnetic circuit and a closed circuit including the last mentioned coil, a source of electro-motive force in said circuit and a translating device controlled by said circuit.

18. The combination with a permanent magnet located in a trackway and connected with the rail on one side of the track so as to have its poles presented to longitudinally separated portions of the rail included in the magnetic circuit of the permanent magnet, a coil on said permanent magnet for diverting or choking the flow of flux from the permanent magnet from the track rail, when it is energized, a circuit and source of current including said coil, a closed track circuit for controlling said circuit, means for controlling said circuit whereby the coil may

- be energized or deenergized, wheels having traveling contact with said trackway, and through which the magnetic circuit of said magnet is adapted to be closed, a coil about 5 said magnetic circuit and a closed circuit including the last mentioned coil, and a translating device controlled by the last mentioned circuit.
19. The combination with a line of rail 10 upon one side of a railway, a permanent magnet magnetically connected therewith at longitudinally separated points, a plurality of wheels having rolling contact with said rail so as to be at times included in a magnetic circuit with the permanent magnet, a coil surrounding a magnetic circuit through 15 said magnet and wheels and a closed circuit for said coil including a translating device.
20. The combination with two lines of 20 rails constituting a railway track, of a plurality of vehicle wheels moving along said track upon each line of rails, track magnets along each line of rails, each of said magnets having its poles presented to longitudinally separated points of the rails upon its 25 side of the track, magnetic conducting means connecting the wheels of a pair, one on each of the said lines of rails and a closed electric circuit including a source of electro- 30 motive force, coils about the said magnetic conducting means, and an electromagnet, the magnetic circuit of a track magnet on one side being closed through the said wheels, the magnetic conductors between 35 them and the track magnet upon the opposite side of the track.
21. The combination with two lines of rails constituting a railway track, of track 40 magnets comprising permanent magnets distributed along said track, of a vehicle moving along said track and having wheels through which magnetic circuit for the track magnets is made, a circuit controlled by the track magnets including a source of electro- 45 motive force and a translating device, the electromotive force of said source being neutralized by the operation of the magnetism of the track magnets as the vehicle passes them, the said magnets operating as described whatever the relative position of the 50 vehicle upon the rails.
22. The combination with a wheeled vehicle traveling along a fixed line of way, of track rails and track magnets adapted to 55 have their magnetic circuits completed through wheels succeeding each other on the same rails and the poles of said magnets being presented to wheels upon one side of said track.
- 60 23. The combination with a wheeled vehicle traveling along a fixed line of way, of track rails and track magnets comprising permanent magnets adapted to have their magnetic circuits completed through wheels 65 succeeding each other on the same rails and the poles of said track magnets being presented to wheels upon one side of said track.
24. The combination with a wheeled vehicle traveling along a fixed line of way, of track rails and track magnets controlled by 70 conditions in the block ahead, adapted to have their magnetic circuits completed through wheels succeeding each other on the said rails, the poles of said track magnets being presented to wheels upon one side of 75 said track.
25. The combination with a wheeled vehicle traveling along a fixed line of way, of track rails, track magnets comprising permanent magnets, adapted to have their magnetic circuits completed through wheels succeeding each other on the same rails, the poles of said track magnets being presented to wheels upon one side of said track, the said permanent magnets being of different 80 strengths at different points along the line of way.
26. The combination with a wheeled vehicle traveling along a fixed line of way, of track rails, track magnets comprising permanent magnets, adapted to have their magnetic circuits completed through wheels succeeding each other on the same rails, the poles of said track magnets being presented to wheels upon one side of said track, the 85 said permanent magnets being of different strengths at different points along the line of way and means controlled by the magnetism in said circuits for slowing the vehicle.
27. The combination with a wheeled vehicle traveling along a fixed line of way, of track rails, track magnets comprising permanent magnets, adapted to have their magnetic circuits completed through wheels succeeding each other on the same rails, the poles of said track magnets being presented to wheels upon one side of said track, the said permanent magnets being of different 90 strength at different positions along the line of way, a coil about the magnetic circuit on the vehicle through which the track magnets have their magnetic circuits completed and a circuit for said coil including a translating device.
28. The combination with a wheeled vehicle traveling along a fixed line of way, of track rails, track magnets comprising permanent magnets of different strengths at 95 different positions along the line of way, said magnets having their magnetic circuits completed through wheels succeeding each other on the same rails, the poles of said track magnets being presented to the wheels upon one side of said track, a coil about the 100 magnetic circuit on the vehicle through which the magnets are adapted to have their circuits completed, and a closed circuit for said coil comprising a source of electromotive force in connection with said coil, and 105

- a translating device, whereby at a predetermined vehicle speed the electromotive force in connection with said coil is varied with a change of strength of said magnets.
- 5 29. The combination with a wheeled vehicle traveling along a fixed line of way, of track rails, track magnets comprising permanent magnets of different strengths at different positions along the line of way,
- 10 said magnets having their magnetic circuits completed through wheels succeeding each other on the same rails, the poles of said track magnets being presented to the wheels upon one side of said track, a coil about the
- 15 magnetic circuit on the vehicle through which the magnets are adapted to have their circuits completed, and a closed circuit for said coil comprising a translating device, whereby the electromotive force in connection with said coil is varied with a change of speed of the moving vehicle.
30. The combination with a wheeled vehicle traveling along a fixed line of way, of track rails, track magnets comprising permanent magnets of different strengths at different positions along the line of way, said magnets having their magnetic circuits completed through wheels succeeding each other on the same rails, the poles of said track
- 25 magnets being presented to the wheels upon one side of said track, a coil about the magnetic circuit on the vehicle through which the magnets are adapted to have their circuits completed, a closed circuit for said coil
- 30 comprising a translating device, whereby at a predetermined speed the translating device will be operated when passing a permanent magnet of a certain strength value and not operated in passing permanent magnets of
- 35 different strength value.
31. The combination with a line of rails upon one side of a railway track, of a vehicle having a plurality of wheels moving along said line of rails and a track magnet
- 40 having its poles presented to longitudinally separated points of the rails upon one side of the track and adapted to have its magnetic circuit completed through wheels succeeding each other on said line of rails, a
- 45 magnetic yoke extending between said wheels upon the vehicle, a coil about the magnetic circuit through said wheels and
- 50 yoke and a circuit for said coil including a translating device.
32. The combination with a line of rails upon one side of a railway track, of a vehicle having a plurality of wheels moving along said line of rails and a track magnet having its poles presented to longitudinally separated points of the rails upon one side of the track and adapted to have its magnetic circuit completed through wheels succeeding each other on said line of rails, a magnetic yoke extending between said wheels upon the vehicle, a coil about the magnetic circuit through said wheels and yoke and a circuit for said coil including an electromagnet controlling the vehicle braking.
33. The combination with a wheeled vehicle traveling along a fixed line of way, of track rails, track magnets comprising permanent magnets, adapted to have their magnetic circuits completed through wheels succeeding each other on the same rails, the poles of said track magnets being presented to the wheels upon one side of said track, a device controlled by the magnetism in the magnetic circuit on the vehicle which is completed through the wheels and track magnet and means for causing the proper operation of the said device regardless of the turning of the vehicle end for end on the rails.
34. The combination with a wheeled vehicle traveling along a fixed line of way, of track rails, track magnets comprising permanent magnets, adapted to have their magnetic circuits completed through wheels succeeding each other on the same rails, the poles of said track magnets being presented to the wheels upon one side of said track, a device controlled by the magnetism in the magnetic circuit on the vehicle which is completed through the wheels and track magnets and means for causing the proper operation of the said device regardless of the direction of movement of the vehicle upon the rails.

Signed at city of New York in the county of New York and State of New York this 27th day of July A. D. 1914.

WILLIAM CONRAD NEIN.
